Inventor:

Robert J. Kehl,

By *Byron Townsend Brickman,*
Attorney.

UNITED STATES PATENT OFFICE.

ROBERT J. KEHL, OF NEWARK, NEW JERSEY, ASSIGNOR TO OXWELD ACETYLENE COMPANY, A CORPORATION OF WEST VIRGINIA.

DESIGN FOR A PRESSURE-REGULATOR CASING.

Application filed April 15, 1926. Serial No. 17,308. Term of patent 14 years.

To all whom it may concern:

Be it known that I, ROBERT J. KEHL, a citizen of the United States, residing at Newark, in the county of Essex and State of New Jersey, have invented a new, original, and ornamental Design for a Pressure-Regulator Casing, of which the following is a specification, reference being had to the accompanying drawing, forming a part of this application, wherein—

Fig. 1 is a side view, Fig. 2 is a top view, and Fig. 3 is a bottom view of a pressure regulator casing embodying the invention.

I claim:

The ornamental design for a pressure regulator casing substantially as shown.

ROBERT J. KEHL.
